WELL CASING PERFORATOR

George F. Turechek, Los Angeles, and Will H. Lindsay, Jr., Lawndale, Calif., assignors to Lane-Wells Company, Los Angeles, Calif., a corporation of Delaware

Application July 25, 1949, Serial No. 106,568

5 Claims. (Cl. 102—20)

1

This invention relates to perforators adapted to be lowered into boreholes, particularly oil and gas well boreholes, for the purpose of piercing or perforating the casing therein or surrounding formations or both, at one or more points. More particularly it pertains to perforators of the aforesaid type, adapted and intended to use detonating explosives of high velocity and of the general character and form known as "shaped charges," as, for example, the type disclosed in U. S. Patent No. 2,399,211 to C. O. Davis et al., issued April 30, 1946.

Early perforators employing either one shaped charge, as in the beforementioned patent, or a number of such shaped charges, were expendable structures, being entirely destroyed when fired, with only the firing line or supporting conductor cable being recovered from the borehole. Such perforators, adapted to hold the shaped charges, were constructed of various materials such as sheet metal, cement or suitable plastics. Expendable perforator devices such as these had a number of disadvantages, among them being high cost, the leaving of debris in the borehole, the subjecting of the surrounding casing to high stresses, and also the inability to selectively fire less than all of the shaped charge units contained in them simultaneously, lest the unfired charges be destroyed by those fired.

It soon was evident that the beforementioned disadvantages could be obviated and other advantages realized by employing retrievable perforator devices for containing the shaped charges and which would be reloaded repeatedly and could be constructed in separate units capable of being separately fired.

In subsequent attempts to develop a retrievable perforator device, the body thereof was formed of a relatively thick walled steel tube having a plurality of longitudinally spaced, laterally directed ports, and the shaped charge units were mounted in relatively light, expendable cylindrical liner assemblies of fibre, plastic or other suitable frangible material and such assembly adapted to be inserted axially into the bore of the said tubular body of the perforator. Such liner assembly was arranged to position each shaped charge unit in precise radially directed alignment with the center of its respective port in the wall of the perforator body.

However, it was found that, after one or several firings, the perforator body, which was subject to the general explosive force extending in all directions from the shaped charge unit, became elongated or otherwise distorted to such

2

an extent that upon reloading with a new shaped charge liner assembly, at least some of the charges failed to register accurately with the body ports and were, in frequent instances, misaligned therewith sufficiently to cause the penetrating blast or jet projected from the shaped charge unit, when fired, to graze or partially strike the edge of the port with resultant damage to it of such an extent that a fluid tight fit could no longer be obtained between the port closing seal disc and the port. Furthermore, the resulting interference with the penetrating jet from the charge, at such a point relatively close to the forward, shaped end of the charge, reduced, to some extent, its desirable penetrating qualities.

It is therefore an object of the invention to provide a perforator structure for shaped charge perforator units, which is not destroyed on first use but can be retrieved from the well, reloaded and reused repeatedly without substantial damage to it or impairment in its working efficiency.

Another object is to provide a novel and improved method as well as a simple and inexpensive means, for mounting the explosive, shaped charge units in the perforator device.

Still another object is to position and to maintain the shaped charge units accurately located and positively held in alignment relative to the ports in the perforator body even after the body may have undergone distortion from the detonation of prior charges.

Still another object is to provide an improved method and apparatus for loading and mounting shaped charge units individually in a perforator body.

The objects of the present invention are accomplished in general, by providing a shaped charge type perforator having a heavy walled, cylindrical body containing a plurality of radially directed ports therein and in which the shaped charge or charges are each individually and independently mounted in accurately aligned position with respect to the center of each port and by means cooperating with each port in the perforator, independent of the overall dimensions of the perforator body, thereby minimizing if not entirely avoiding the ill effects from distortion created by prior and repeated use of the perforator.

Other objects, advantages and features of novelty of the invention will be evident hereinafter.

In order to illustrate one preferred embodiment of the invention and the manner of its use, at-

tention is now directed to the accompanying drawings, in which:

Figure 1 is a view, partly in elevation and partly in longitudinal section, of a completely assembled perforator ready to be lowered into a well bore-hole.

Figure 2 is a transverse sectional view, on an enlarged scale, taken on line 2—2 of Figure 1 but showing a typical shaped charge unit therein partly in plan view and partly in section; and

Figure 3 is an exploded view in perspective of the parts for securing a shaped charge unit in place in the perforator body.

The perforator apparatus comprises a perforator body 10, as shown in Figures 1 and 2, in the form of a thick walled, elongated tube or cylinder, closed at its lower end by a tapered bull plug 11. The thick wall of the body 10 has a series of longitudinally spaced, radially directed openings or ports 12 extending therethrough to the inside of the central bore or chamber 13, each port being enlarged on the outside by a short counterbore 15. Such series of ports 12 (only two of which are shown in Figure 1 for the reason that for convenience of illustration the view of the gun body 10 is shortened by cutting away, for the most part duplicate portions thereof) may be arranged along the body 10 in any desired pattern. One suitable arrangement which is frequently used is to place the ports 12 in a spiral pattern along body 10.

At each port 12 a shaped charge unit such as shown at 16 is adapted to be mounted so that the jet shaped blast projected from the forward end thereof will issue through the center of the port. To assist in positioning and accurately maintaining each such charge 16 in centered relation to its respective port 12, the inner wall of gun body 10, diametrically opposite each port, is provided with suitable means to engage the rear end of the charge unit. Preferably such means takes the form of a radially directed cylindrical recess 17, and the adjacent rear end 18 of the charge is cooperatively shaped to fit within the recess 17.

To support the other end of the shaped charge unit 16, securing means are inserted through port 12 to retain charge 16 in place and to maintain end 18 seated in recess 17, such securing means also serving to support and to center the adjacent forward end of charge 16 in axial alignment relative to the center of its port 12. Such securing means comprises an annular charge aligner diaphragm or ring member 20, of suitably rigid material, such as for example, thin sheet aluminum, brass or steel. The aligner diaphragm 20 is adapted to fit snugly within a short counterbore 22 formed in the forward or larger end of the shaped charge unit and to be pressed in engagement with an internal abutment shoulder 23 formed at the bottom or inner end of the said counterbore as best shown in Figure 2. The aligner diaphragm 20 is formed with an integral approximately conical outer marginal portion 25 and an inwardly turned, inner marginal portion 26 terminating in a narrow transversely or radially extending flanged portion 27, thereby providing an inner annular recess terminated by the annular seat formed by said flanged portion 27. The aligner ring member 20 is pressed into counterbore 22 of charge unit 16 before the latter is inserted into the axial bore 13 of gun body 10 and when the shaped charge unit 16 is properly positioned opposite its port 12, and the rear end portion thereof seated in recess 17, seat 27 of aligner ring 20 will be directly in axial alignment with the center of

port 12. An annular expandable member or sleeve 30 is adapted to be inserted through port 12 into recess 26 and seated against shoulder 27 to secure charge unit 16 in place. Member 30 preferably takes the form of a sleeve as best shown at 30 in Figure 3 of any suitable material such as fibre or plastic and of an external diameter to fit, with slight clearance, the inside diameter of the port 12. Sleeve 30 is slotted longitudinally at a plurality of circumferentially spaced points as shown at 31 and the tongues 32 so formed may, in some cases, have an outward or radial set or bias in order to securely grip the wall about port 12. However, in order to make the sleeve member 30 adaptable for securing charge units 16 in place after the gun body has been used a number of times and the blasts of the charges may have expanded and slightly distorted port 12, the wall of the split member or sleeve 30 is preferably tapered in thickness by an increasing internal diameter toward its slotted end as indicated in Figure 2, and a mating inner sleeve 33 is formed with the wall similarly tapered by a decreasing outside diameter toward the inner end, and this sleeve 33 is adapted to be thrust into sleeve 30 and thus utilized positively to expand the slotted portion of sleeve 30 into gripping engagement with the inside surface of the port 12. The tapers on these two sleeves 30 and 33 are the same and are such as to be frictionally self-locking upon one another so that when sleeve 33 is forcibly pressed or hammered into split sleeve 30 the tongues of the latter are expanded radially and locked in position in frictional engagement with inside surface of the wall of port 12 and the sleeves 30 and 33 will not separate axially with respect to one another under the wedging force thus applied. The splits or slots 31 in sleeve 30 permit wide expansion of the thus formed tongues 32 of this sleeve so that it will function equally well after ports 12 have become considerably expanded through extended use. The thin metal of which the aligner ring 20 is preferably constructed gives this ring a certain axial flexibility so that it may maintain a spring-like axial force on charge unit 16 urging it rearwardly sufficiently to keep the small end 18 thereof firmly seated in recess 17. The close fit of aligner ring 20 in counterbore 22 of charge unit 16 and of sleeve 30 in recess 26 maintains charge unit 16 at all times in rigid axial alignment with port 12.

For convenience, reference character 16 has heretofore been utilized to indicate the charge unit as a whole including the explosive contents and its container but it actually indicates the casing for the charge of explosive A, which may be of the detonating type described in the above-mentioned Davis et al. Patent No. 2,399,211, shaped or molded with a suitable concavity or conical depression therein facing toward port 12 as shown in partial section in Figure 2. The casing 16 for the shaped explosive charge may be of any suitable material such as Bakelite, Lucite, etc. The small or rearward end 18 of the charge unit 16 has an opening or passage 35 extending transversely therethrough to receive a detonating fuse or cord as shown at 36. As shown, the forward end of charge unit 16 is of greater diameter than that of port 12 and has its forward face rounded as viewed in Figure 2 to conform generally to the inside surface of bore 13 of body 10.

In loading the perforator body, charge units 16 are inserted one at a time, and each is individually mounted in accurately positioned relation to its

respective port as hereinafter described. The method is as follows:

Fuse cord 36 is first passed through the fuse passage 35 of the first charge unit and an aligner diaphragm ring 20 is pressed into the counter-bore 22 in the forward end of the charge unit casing; the charge unit is then preferably inserted through the upper open end of the perforator body and lowered or moved longitudinally therein to the level of the lowest or bottom port in the body. Tongs to grip the charge unit may be utilized for this purpose and a suitable form of such tongs are shown and described in the copending application of Will H. Lindsay, Jr. and Robert A. Phillips, Serial No. 106,567, filed July 25, 1949.

The charge is manipulated by the tongs and through port 12 to align rear end 18 thereof with the lowest inner body recess 17 and to push the end of the charge into the said recess. Split sleeve 30 is then inserted through port 12 and forced into seating engagement against flanged seat 27 on the aligner diaphragm 20, thereby centering charge unit 16 relative to the port 12 and putting diaphragm 20 under slight axial compression to maintain rear end 18 of the charge unit, forced into recess 17 in the inner opposite wall of gun body 10. If needed, inner tapered sleeve 33 is then forced into the split end of sleeve 30 to expand the latter and positively lock it in place in the port opening, sleeve 33 being always used when port 12 has been enlarged or distorted from the firing of previous charges. With the lowest charge securely in place a sealing disc or cap 37, of copper, brass or other suitable material, is forced into counter-bore 15 of the port 12 to prevent ingress of any fluid which may surround gun body 10 when the apparatus is lowered into and submerged in fluid in a borehole. The above steps are repeated with each succeeding charge unit, fuse 36 being threaded through the bores 35 and aligning diaphragm 20 being mounted in each charge 16 in succession before the charge is inserted into the axial bore 13 of the perforator body 10.

When the perforator body 10 has been completely loaded and all ports sealed by seal discs as shown at 37, a cap supporting washer 34 carrying a blasting cap union 38 which is crimped to the end of the ignition cord 36, is placed in the open end of body 10 and is secured in place, as shown, by threaded bushing sleeve 40 which makes threaded engagement at 41 with the inner, upper end portion of the wall of the perforator body 10. A detonating cap 42 to which a flexible insulated conductor 43 is secured, is fastened to the upper end of the blasting cap union 38 before casing 44 and cable head 45 are secured in place. Fluidtight packings are provided at 46 and 47 to seal the upper end of body 10 against entrance of fluid. A conductor cable 49 of conventional design attached to the top of the cable head 45 serves as a means to lower the perforator into the well and to conduct the firing current to the firing mechanism. The electrical connections between conductor 43 and the conductors in the conductor cable 49 are of conventional design and are contained in the cable head assembly 45, the lower end of which fits within the bushing sleeve 40 and makes threaded engagement with the latter as shown at 50.

From the foregoing it will be apparent that the present invention provides an improved form of perforator apparatus adapted to repeated use

with high explosive shaped charge units, that the individually mounted charges are always accurately positioned and centered relative to the discharge ports regardless of distortion of the perforator body, and that the invention provides a novel method and apparatus for loading a shaped charge perforator.

While the invention has been herein described in what are now believed to be the preferred forms of its method and apparatus aspects, it is to be understood that the invention is not limited to the specific details of such forms but covers all modifications, changes and adaptations within the scope of the appended claims.

What is claimed is:

1. In apparatus for perforating well casings the combination comprising: a body having an axial bore therein; a series of radial ports extending from said bore through the wall of said body and disposed at intervals longitudinally of said body; a series of shaped charges within said bore, each charge being directed toward one of said ports; interengaging means on each charge and on the wall of said body diametrically opposite each port in said body; and aligning means extending from each said port to each said charge for securing the charge in place accurately centered as to its port, said aligning means comprising a ring engaging the forward end of each charge, an expansible sleeve inserted through the port and against said ring, and an inner tapered sleeve forced into the inside of said expansible sleeve to expand the same into frictional engagement against the inner walls of the port.

2. In apparatus for perforating well casings the combination comprising: a body having an axial bore therein and a series of radially directed ports extending from said bore through the wall of said body and disposed at intervals longitudinally of said body; a series of shaped charges within said bore, each charge being directed toward one of said ports; interengaging means on each charge and on the wall of said body diametrically opposite each port in said body, and aligning means extending from each said port to each said charge for securing the charge in place accurately centered as to its port and for directing the blast from the charge through the center of the port, said aligning means comprising an annular member fitting the forward end of each charge and formed with a concentric inner recess, a split sleeve extending from within the port and into seating engagement in said recess in said ring, and a tapered inner sleeve forced into said split sleeve to expand the said split sleeve against the walls of the port.

3. Apparatus for securing a shaped charge within a perforator body having an axial bore and a radial port extending from said bore through the wall of said body, said charge being insertable through said bore to a position to fire through said port, said apparatus comprising: an aligning ring to be fixed coaxially to said charge before insertion into said bore, said ring providing a coaxial, cylindrically shaped recess therein; an outer split sleeve making a slidable fit within said port and positioned in endwise seating engagement within said recess, said split sleeve having an outwardly increasing inside diameter; an inner sleeve having an inwardly decreasing outside diameter matching the inside of said outer split sleeve and adapted to be forced into said outer split sleeve to expand said outer

sleeve into frictional engagement with the walls of said port.

4. Apparatus for securing a shaped charge within a perforator body having an axial bore and a radial port extending from said bore through the wall of said body, the bore wall having a recess formed in the inner surface thereof diametrically opposite said port, said charge being insertable through said bore to a position to fire through said port, said apparatus comprising: an aligning ring to be fixed coaxially to the forward end portion of said charge and providing a coaxial, cylindrically shaped recess therein; an expansible sleeve member adapted to make a 15 slide fit within said port and positioned in end-wise seating engagement with said last recess; and an inner cylindrical member having a tapered outside diameter, positioned in said outer split sleeve to expand said outer expansible sleeve into frictional engagement with the walls of said 20 port whereby said charge may be held in port alignment position with the rear end thereof seated in said first recess.

5. Apparatus for supporting the forward end of a concave shaped charge unit, circular in cross- 25 section, within a perforated body, which body has an axial bore and a radial port extending from

said bore through the wall of said body, said apparatus comprising an aligning ring to be fixed to the circular forward end of said shaped charge unit at the concave end thereof between such concave end of the charge unit and the inner wall of said bore, said aligning ring having a central opening coaxial with said charge unit and an outwardly facing circular shaped recess concentric with said central opening, a tubular sleeve having an inner end arranged to be received in said recess with the body of the sleeve spanning the distance between said ring and the inner wall of said bore and with the outer end of said sleeve being expansible and extending into said port, and tubular means insertable into the outer end of said sleeve for expanding said sleeve into binding engagement with the wall of said port.

GEORGE F. TURECHEK.
